UNITED STATES PATENT OFFICE

149,052

DESIGN FOR A WRENCH

Arny O. Elnes, Duluth, Minn., assignor of one-half to Clarence H. Taylor, Duluth, Minn.

Application August 28, 1946, Serial No. 132,923

Term of patent 14 years

(Cl. D54—16)

To all whom it may concern:

Be it known that I, Arny O. Elnes, a citizen of the United States, residing at Duluth, in the county of St. Louis and State of Minnesota, have invented a new, original, and ornamental Design for a Wrench, of which the following is a specification, reference being had to the accompanying drawing, forming part thereof.

In the drawing:

Fig. 1 is a side elevational view of a wrench showing my new design;

Fig. 2 is a back plan view of Fig. 1.

I claim:

The ornamental design for a wrench, as shown.
ARNY O. ELNES.
